UNITED STATES PATENT OFFICE.

GEORGE S. BLAKEMAN, OF PAXTON, INDIANA.

FENDER.

SPECIFICATION forming part of Letters Patent No. 357,654, dated February 15, 1887.

Application filed October 28, 1886. Serial No. 217,439. (No model.)

To all whom it may concern:

Be it known that I, GEORGE S. BLAKEMAN, a citizen of the United States of America, residing at Paxton, in the county of Sullivan and State of Indiana, have invented certain new and useful Improvements in Fenders, of which the following is a specification, reference being had therein to the accompanying drawings.

10 This invention pertains to certain new and useful improvements in fenders; and it consists in the detailed construction, combination, and arrangement of the parts, substantially as hereinafter fully set forth, and particularly pointed out in the claims.

15 In the accompanying drawings, Figure 1 is a view in front elevation of my invention. Fig. 2 is a view of one of the doors or sections, and Fig. 3 is a detail view.

20 In carrying out my invention I employ two uprights or standards, A, which are provided at suitable distances apart with apertures *aa*, whereby the same, together with their right-angular foot portions *a' a'*, are secured to the 25 wall or partition on either side of the grate to which it is designed to apply my invention. These standards are provided with the above-referred-to feet *a'*, as additional means of securing the same in position, and to the front 30 surface of each standard, near the upper and lower ends thereof, are secured two outwardly-projecting eyebolts, *b b*.

35 B' B' are two doors or sections, composed each of two end bars, *b' b''*, to which are secured the ends of curved horizontal bars *b³*, said bars being outwardly bent at *b³*, as shown. To the rear side of each outer bar *b'* is secured a hinging rod, C, said rod being passed through the eyebolts *b* of each standard A 40 and its right-angularly-bent ends secured in apertures in said outer uprights. On the outer surface of the two inner or meeting bars, *b''*, of the doors or sections are secured the ends of approximately -U-shaped clasps *d*, said 45 clasps extending in opposite directions, so as to provide for the secure retention in position of said doors or sections when closed, as shown in Fig. 1.

D is an approximately -T-shaped sliding bolt, having the upper and lower ends of its vertical portion loosely secured on two of the curved horizontal bars *b²*, and its horizontal portion projects through corresponding apertures, *d'*, formed in each inner upright, *b''*, whereby the doors or sections are securely held in position, in addition to the U-shaped clasps. To one of the curved bars or rods *b²* is secured, on the inner side, one end of an inwardly-projecting right-angular arm, E, the object of which is to prevent the swinging 55 of the doors or section too near the grate, said arm striking against said grate in such event.

It will be seen that by pulling on the vertical portion of the approximately -T-shaped bolt D the horizontal portion thereof will be withdrawn from the aperture in the opposite or adjoining end upright, thus permitting of the opening first of the door or section B', thence the other corresponding door or section, the hinging of said doors or sections being effected as herein described.

Having thus fully described my invention, what I claim, and desire to secure by Letters Patent, is—

1. The combination of the apertured standards having eyebolts, the doors or sections constructed with perforated upright meeting bars, the hinging rods secured to said doors or sections, and the sliding bolt having its vertical portion encasing two of the horizontal bars of one of said sections or doors, substantially as shown and described.

2. In a fender, the combination, with the hinged sections or doors having curved horizontal bars, perforated upright meeting bars, 85 and the U-shaped clasps, of the T-shaped sliding bolt having its vertical portion encasing two of said horizontal bars of one door or section, substantially as shown and described.

In testimony whereof I affix my signature in presence of two witnesses.

GEORGE S. BLAKEMAN.
